CLAIM

The ornamental design for a pallet, substantially as shown and described.

DESCRIPTION

FIG. 1 is a perspective view of a pallet showing my new design;

FIG. 2 is a top plan view thereof;

FIG. 3 is a front elevational view, the rear being a mirror image thereof;

FIG. 4 is a right side elevational view, the left side being a mirror image thereof;

FIG. 5 is a bottom plan view thereof;

FIG. 6 is an enlarged, fragmentary, top plan view of the lower right hand corner portion of FIG. 2 showing the surface ornamentation thereof in detail;

FIG. 7 is a perspective view of a pallet showing a second embodiment of my new design;

FIG. 8 is a top plan view of FIG. 7;

FIG. 9 is a front elevational view of FIG. 7, the rear being a mirror image thereof;

FIG. 10 is a right side elevational view of FIG. 7, the left side being a mirror image thereof; and

FIG. 11 is a bottom plan view of FIG. 7.
